TOOL HEAD UNIT

Ernest L. Fickett, William O. Forman, and Roland G. Holmes, Fitchburg, Mass., assignors to Fitchburg Engineering Corporation, Fitchburg, Mass., a corporation of Massachusetts

Application May 6, 1932, Serial No. 609,694

7 Claims. (Cl. 90—16)

This invention relates to a head for carrying a milling, boring, drilling or other tool, which unit is self-contained and can be applied to a planer or other convenient type of machine tool. 5 The principal objects of the invention are to provide a self-contained construction in which the head proper with the motor can be turned to different angles, about the axis of the tool spindle, on the base by which it is secured to the 10 bed or frame of the machine to which it is applied; to provide an arrangement for driving the tool spindle from the motor in which the pick-off or other gears for changing speed are located at a point in the train such that one of them 15 is on the shaft of a worm which operates the slow motion drive for the spindle; to provide a perfect acting binding means for the quill which will prevent vibration and loosening at both ends of the quill; to provide a pump actuated 20 by the operation of the driving gear for lubricating the machine, and to provide the entire construction in such form that all aligning surfaces on which the spindle alignment depends can be bored from a common axis, thus permitting the 25 accurate alignment of the several co-related parts.

Other objects and advantages of the invention will appear hereinafter.

Reference is to be had to the accompanying 30 drawings, in which

Fig. 1 is a vertical diametrical sectional view of a preferred embodiment of the invention;

Figs. 2 and 3 are bottom plan views showing the motor and the speed transmission mechanism 35 adjusted to two different positions;

Fig. 4 is a view, partially diagrammatic, of the driving gearing;

Fig. 5 is a sectional view on the line 5—5 of Fig. 1 showing one of the means for binding the 40 quill;

Fig. 6 is a central sectional view at right angles to Fig. 1, and

Fig. 7 is a view similar to Fig. 1 showing the invention carried out with certain modifications.

In the form shown in the first six figures, the unit is built with the idea of applying it to the bed of a planer by means of a rail, housing or other support along the side of the planer in a vertical plane and a supporting part comprising 50 a cylinder 10 constituting a part of the unit and having suitable gibbed ways 11 by which it is secured to the rail along the side of the planer to permit it to be moved horizontally in a well known way and secured in fixed position.

This cylinder 10 is provided, preferably on the

top therof, with a casing 12 secured to the top of the cylinder 10 by bolts 13 arranged in a circle and capable of being turned and fixed in another place so that this casing 12 can be located in two or more positions. The casing 12 is fitted into the end of the cylinder 10 with a spigot or swivel joint centrally located with respect to the circle of bolts 13 and the axis of the cylinder. When a change is to be made in the position of the motor, the casing 12 can be revolved on its support by hand and brought to the right location most desirable for the particular machine to which it is applied. It is to be understood that this motor change is done ordinarily at the shop where the machine is manufactured and it is not intended that it will have to be changed again unless the machine is taken off one kind of quantity production and put on another, when such a change would have to be made.

At one end this casing is provided with a motor 14 for operating the whole machine and in Figs. 2 and 3 the motor is shown located in two different positions owing to the fact that the casing 12 in the two cases has been turned around 90°. Ordinarily this motor is flange mounted on the combination cover plate and gear box cover 12.

The motor operates a pair of shafts through gears 15 and 16 and also through a pair of pick-off gears 17 and 18. The gear 15 is located on the motor shaft. The gears 16 and 17 are located on a back shaft and the gear 18 is located on the shaft which carries a worm 19 as shown in Fig. 4. The gears 17 and 18 are held on their shafts by nuts 20 or the like and obviously they can be removed and another pair having a different gear ratio substituted to provide for different speeds.

As will be explained later the worm 19 drives a tool. To have one of the bottom gears located on the shaft of this worm simplifies the whole driving construction very materially and permits all necessary changes by the simple and well known expedient of removing these gears and replacing them by others. Of course a quick change gear box of any ordinary construction can be substituted for the pick-off gears.

The worm 19 drives a worm gear 21 which is bolted to a worm wheel carrier 23 by fitted bolts extending through suitable flanges. The worm wheel carrier is supported at opposite ends by roller or ball bearings which absorb both the radial and thrust loads on the worm wheel. This worm wheel carrier is splined to a tool spindle

22 by one or more keys 24 which are shown as having headed ends. This spindle is hollow, preferably. The spaces outside these ends are filled with solder at 25 under certain circumstances to 5 prevent oil passing in through the keyways.

On the worm carrier 23 is an eccentric 26 which operates a pump piston 27 against a spring 28 for supplying oil to the various bearings. The usual inlet and outlet passages are provided in 10 the pump and oil is directed through suitable piping to any bearings, not dipping in the oil. The drive unit is sealed against loss of lubrication by means of suitable oil seals 29 at top and bottom, these oil seals being pressed into the casing and 15 engaging the worm carrier 23. This enables the device to carry a head of lubricating oil in the box.

The tool spindle 22 extends down through the center of the spigot joint into the cylinder 10 and into the quill 30 carried by this cylinder, by 20 which it is supported. Adjustment is secured by means of lock nuts 31 bearing on the top of the anti-friction bearings on the quill which carry this end of the spindle. The quill is provided with means by which it can be bound in place in such 25 a way as to prevent vibration at one end or the other. This is done by the simple expedient of employing two quill binders 32, one located near one end and the other near the other. This obviously binds both ends of the quill so that even 30 after wear there will be no looseness. These quill binders are made in the form of a screw having one binder under the head and the other binder being taken up by the turning of the screw, as shown in Fig. 5. These binders have concave 35 surfaces fitting the quill so that, whenever they are tightened up, the quill is acted on equally by both of them and is moved back against the other inside surface of the cylinder 10 where it has a firm bearing.

40 The tool spindle as shown in this figure is provided with a standard taper to receive a milling cutter 34, drill, or the like. It also has a flanged end 35 on which large cutters may be bolted as will appear. An adjusting gear 43 meshing with 45 a rack 44 on the quill and operated by a wrench on a squared shaft 45 is shown for moving the quill in an axial direction for adjustment.

A cover 36 is detachably mounted on the cylinder 10 over a passage through which it is possible to get at the lock nuts 31 to adjust the roller bearings which support the spindle without removing the quill from the housing.

In this form a cover plate 37 is located at the 55 end or top of the casing 12 removably mounted and provided with a sealing plate 38 which receives the upper oil seal 29 and the cover plate itself carries the anti-friction bearings at this end.

60 In the form shown in Fig. 7, the cylinder 10 and casing 12 are in one piece designated 40. This construction can be used in places where there is no need of changing the position of the motor. Obviously the machine can be made with these 65 two parts fixed together in any position and conditions under which it is to be used permanently.

In this form is shown the flanged end of the spindle 22 having a large milling cutter 41 bolted to it and driven by means of a key 42.

70 It will be noticed that in the form shown in Fig. 1 the hollow spindle passes through the box 38 to the outside but where it can be done it is desired to house this spindle entirely within the structure and for that purpose a different construction is used at the end and shown in Fig. 7.

This involves the cap 37 which supports the anti-friction bearings as before and in place of the seal 38 is provided a cylindrical member 47 carrying a cap 48 which cap is removably mounted on it by bolts. When these parts are all fixed in place, this end of the device is closed and it is intended that this closure be permanent for all practical purposes, although each member, of course, can be taken out. This structure provides for the sealing of the end of the casing against entrance of dust or dirt without the loss of oil, without providing any oil sealing devices or the like at this end. In this form is shown a cover 46 for the gear train.

80 It will be seen therefore that this invention involves in one of its forms an adjustment for the parts supporting the motor so that the motor can be placed in the most convenient location; that one of the pick-off gears is located on the worm shaft, thus reducing the gearing; that the quill is held back against its bearing surface throughout its entire length and that the oil pump is arranged in a convenient position and operated without any unnecessary mechanism. Also the 85 milling unit is self-contained and preferably, but 100 not necessarily, consists of two parts adjustably mounted with respect to each other. On account of the employment of the cover 36 it is possible to get at the lock nuts which adjust the anti-friction bearings supporting the spindle, without 105 removing the quill from the housing. Also the inner and outer spindle bearings can be lubricated without removing any caps, covers or the like.

110 Although we have illustrated and described only two forms of the invention we are aware of the fact that other modifications can be made therein by any person skilled in the art without departing from the scope of the invention as expressed in the claims. Therefore we do not wish to be 115 limited in this respect otherwise than as set forth in the claims, but what we do claim is:

1. A tool head unit comprising a supporting part, a quill supported therein, means for clamping the quill in position, a casing swiveled on the 120 supporting part on the same axis as the quill and adapted to be turned thereon, a motor projecting from one side of the casing with its axis at an angle to the axis of the quill means in the casing driven from the motor for operating the 125 quill, and means for securing the casing in the desired position about the center of the supporting part to hold the motor in the desired position.

2. In a tool head unit for application to a machine tool, the combination of a supporting element adapted to be adjusted along the bed of a machine tool, a quill carried inside the said supporting part, a tool spindle, said quill having bearings for supporting the tool spindle therein, a casing swiveled on the supporting element on 130 the same axis as the quill and adapted to be secured in adjusted positions around that axis, a motor carried by the casing, a worm wheel mounted on the spindle in said casing, means carried by the casing for rotating the worm wheel 135 from the motor and anti-friction bearings carried by the casing for the part of the quill that extends into the casing.

3. In a tool head unit, the combination of a quill, means for supporting the quill in adjusted 140 positions, a tool spindle carried by the quill, supporting bearings in the quill for the spindle, a casing located beyond the quill, said spindle projecting into the casing, a motor carried by the casing, a worm in the casing, a set of gearing 145

- comprising replaceable change speed gears, one of which is on the shaft of said worm, for driving the worm from the motor, a worm wheel in the casing secured to the spindle and meshing with said worm, and bearings in the casing for the part of the spindle that projects into the casing. 80
4. A self-contained unit for supporting a tool comprising a supporting member adapted to be mounted in adjusted positions on the frame of the 10 machine tool, a quill carried thereby, a tool spindle passing through the quill, anti-friction bearings in the quill for supporting the tool spindle, a second element comprising a casing having bearings for said spindle, a motor on the casing, and means 15 in the casing for rotating the spindle from the motor, said casing being adjustable about the axis of the spindle to change the position of the motor from one side to another of the first-named member. 90
5. In a driving means for a tool head, the combination with a casing in which a tool spindle is supported, of a motor having a casing fixed to the outside of the first-named casing, a pinion on the shaft of the motor in the casing, a back shaft, 25 a gear on the back shaft meshing with the pinion, a worm, a shaft on which the worm is fixed, a pair of pick-off gears carried by the last two shafts and meshing with each other for driving the worm at different speeds, a worm wheel meshing with the worm to be driven thereby, and a 30 worm wheel support to which said worm wheel is secured, said worm wheel support being keyed to the spindle for driving it. 100
6. In a tool head unit, the combination of a 35
- 40
- 45
- 50
- 55
- 60
- 65
- 70
- 75
- casing, a motor supported on the outside of said casing, a worm in the casing, a worm gear meshing with said worm, a tool spindle, means below said casing for supporting the spindle, bearings at both ends of the casing for said spindle, a plate at the end of the casing having an internal flange carrying one of said bearings, a sealing plate secured to said plate and extending inwardly through it, a supporting member to which the worm gear is secured, said supporting member being keyed to the spindle and extending through the said sealing plate, and means for forming a tight joint at the point where the supporting member extends through the plate to prevent the escape of lubricant. 85
7. In a self-contained unit for supporting a tool, the combination of a casing having a quill carried thereby, bearings in the casing for said quill, a tool spindle carried and supported by said bearings, a set of bearings beyond the quill in the casing for supporting the end of the spindle farthest from the tool end thereof, said casing having an opening at the end beyond the spindle, a cover plate for closing said opening, said cover plate having means for supporting one of said 105 bearings and having an opening, an open centered member entering the opening and secured to said cover plate, and a cap closing the opening in said member, the cover plate, member and cap being bolted together. 110
